UNITED STATES PATENT OFFICE.

WILLIAM EDWIN NETTLE, PAUL SELBY, JAMES BLYTHE, AND JOSEPH HENRY HOLMAN, OF JOHANNESBURG, TRANSVAAL, SOUTH AFRICA.

RECIPROCATING ROCK DRILL FOR SUPPLYING WATER TO BORE HOLES DURING DRILLING.

Application filed July 21, 1920. Serial No. 398,024.

To all whom it may concern:

Be it known that we, WILLIAM EDWIN NETTLE, a subject of the King of Great Britain, PAUL SELBY, a citizen of the United States, JAMES BLYTHE, a subject of the King of Great Britain, and JOSEPH HENRY HOLMAN, a subject of the King of Great Britain, all residents of Johannesburg, Transvaal Province, Union of South Africa, have invented certain new and useful Improvements Appertaining to Reciprocating Rock Drills, for Supplying Water to Bore Holes During Drilling, of which the following is a specification.

This invention has reference to water-supplying means or attachments for those types of rock-drills and rock-drilling machines called "reciprocating drills."

The kind of water-supplying means to which the invention more particularly relates is that in which the water is led through a tube into the reciprocating parts of the drill, and thence through the bit or steel.

With water-supplying means of the nature referred to, difficulty has been experienced in preventing the water leaking in a backward direction from the water passage or conduit, which is formed through the reciprocating parts, into the cylinder. It is essential that this backward leakage shall be prevented, as it interferes with the due operation of the drill and in time results in serious disorganization thereof.

It is the primary object of this invention to overcome this difficulty, and to attain the desired end in a simple, inexpensive and effective manner. By obviating the difficulty in the manner hereinafter explained, we are able to simplify and improve the general construction of such water-supplying means.

The present invention is characterized by a construction in which provision is made for admitting and maintaining a supply of air under pressure into a space or chamber which is so positioned that the pressure of said air operates in all positions of the piston, to preclude the passage of water in a direction rearwardly of said space or chamber.

In the accompanying drawings we illustrate a practical embodiment of the invention, wherein—

Fig. 1, is a part longitudinal section of a

reciprocating rock-drill incorporating the features of the invention. 55

Fig. 2, is an enlarged detail of the front end of the piston and rear end of the piston rod and those details of the invention associated therewith.

Fig. 3, is an enlarged detail of the connection between the water-supply tube and the back cover of the drill.

Fig. 1 of the drawings shows the complete arrangement, and in this figure, 1 indicates the cylinder of the rock-drill, 2 being the piston, which reciprocates in the cylinder 1. 3 is the piston rod, 4 the chuck or holder for the bit or steel and 5 the bit or steel. 8 is the axial passage or conduit along which the water passes, which passage extends through the aforementioned parts 3, 4, and 5, and terminates at the cutting extremity 9 of the bit or steel 5. 10 is the cylinder back cover, 11 the rifle bar and 12 the ratchet wheel of the rotation mechanism; 12^a the rifle nut, fixed in the rear end of the piston 2 and engaged by the rifle bar 11 in the ordinary manner.

The water supply means include the tube 13, which is connected to and supported by the back cover 10 and extends in a forward direction through an axial hole in the rifle bar 11, through the piston 2 and into the passage or conduit 8, through the piston rod 3. For the purpose of attaching said tube 13 to the back cover and suitably connecting it with the water supply means, the tube 13 is shown constructed with a head or enlargement 14, which is seated in a recess or counterbore 15 in the rear end of a spud or coupling member 16. 17 represents packing between the head or enlargement 14 and the bottom of the recess or counterbore 15. 18 is an elbow piece or bend the outer end of which, 19, is threaded for making suitable connection between it and a hose or other suitable preferably flexible pipe which conveys the water to the machine. 20 is a gland or nut for retaining the elbow or bend 18 in position against the end of the spud or coupling member 16; 21 being packing between a flange 22 formed on the bend and the end of the spud 16. This connection permits the elbow or bend 18 to be rotated about its point of attachment to the spud 16 as may be necessary in manipulating or

working the drill. The spud 16 is screwed into a recess 23 in the back cover 10, and between its front end and the bottom of the recess 23 packing 24 is placed which surrounds the tube 13 and forms a gasket between the back cover 10 and the tube 13. It is to be understood that any other appropriate mode of attaching the water supply tube to the cylinder back cover may be adopted in lieu of that shown and described.

At the rear of the passage or conduit 8 through the piston rod, there is screwed or otherwise secured a nut or bush 25 of brass or other suitable metal or material. The water tube 13 projects forwardly through this nut or bush 25, which has a loose fit on the tube 13, so that the piston 2 can reciprocate freely over it, and at the same time permit a small quantity of the compressed air or actuating fluid to pass between said water tube 13 and bush 25 in a forward direction during the forward stroke of the piston. Around the tube 13, forward of the nut or bush 25, an annular space or chamber 26 is provided which receives a supply of air under pressure in all positions of the piston 2. The diameter of the rear end of the passage or conduit 8 forward of the aforesaid annular space or chamber 26 and the external diameter of the water tube 13 are such as to form or provide clearance to allow air to pass in a forward direction from the annular space or chamber 26 through the passage or conduit 8, and in that way prevent the water passing in a backward direction into the space or chamber 26, whence it would pass into the piston between the exterior of the tube 13 and the bore of the nut or bush 26.

A small hole or port 27 is formed in the front end of the piston which places the cylinder in communication with the space or chamber 26. This port 27, on the backward stroke of the piston 2, allows a small quantity of air under pressure to pass from the interior of cylinder 1 to said space or chamber 26 and thence along the conduit 8 in a forward direction. The compressed air which enters the chamber 26 between the bush 25 and tube 13 on the forward stroke of the piston and the compressed air which enters said chamber through port 27 on the backward stroke of the piston, by passing between the tube 13 and conduit 8, and along conduit 8, precludes the passage of the water in a rearward direction from conduit 8 into the space or chamber 26, as previously explained. It is requisite so to control the supplies of compressed air and water to the drill that the passage of the air into the cylinder takes place before the water passes to the tube.

The construction above described obviates the necessity for the use of packing either at the back or front of the nut or bush and

by admitting of the attachment of the water supply tube to the cylinder back cover it enables the water-holding vessel, which has been connected to the back cover in certain known arrangements, to be dispensed with.

What we claim as our invention, and desire to protect by Letters Patent is:

1. In a rock-drill, in combination, a cylinder, a reciprocating piston in said cylinder, a drill steel operably connected to the piston, said piston and steel having a passage through which water passes to the bore hole, the reciprocated parts having a space which is placed in communication with the cylinder at both the front and back of the piston, and a water supply tube which passes through the piston and said space to convey water to the passage through the reciprocated parts.

2. In a rock drill, in combination, a cylinder, a reciprocating part in said cylinder, a drill steel connected to said part, a passage through said part and steel for leading water to the bore hole, a tube connected to the cylinder and over which the piston works, a chamber in said reciprocated part around the tube, the said part having a port placing the interior of the cylinder at the front of the piston in communication with said chamber to admit and maintain a supply of air under pressure to said space during the backward stroke of the piston, as and for the purpose set forth.

3. In a rock drill, in combination, a cylinder, a reciprocating piston in said cylinder, a piston rod connected to said piston, and a drill steel connected to said piston rod, the piston, piston rod and steel having a passage for leading water to the bore hole, a water supply tube attached to the cylinder and projecting into the piston and communicating with said water passage, one of the reciprocated parts being constructed to form a chamber around said tube and having a port placing said chamber in communication with the cylinder at the front of the piston and a bush which forms a loose guide for the tube at the rear of said chamber, thereby forming a passage which places the cylinder at the back of the piston also in communication with said chamber.

4. In combination, a rock drill cylinder, a reciprocating piston in said cylinder, a piston rod attached to said piston, a drill steel fixed to the front of said piston rod, the piston, piston rod and steel having a passage extending therethrough for leading water to the bore hole, a water supply tube fixed at the rear end of said cylinder and projecting into the aforesaid passage, means for leading water into the rear end of said tube, the reciprocated parts having a chamber surrounding the tube and a port placing said chamber in communication with the cylinder at the front of the piston, and a

bush loosely surrounding the tube and forming the rear of the chamber, and providing a passage which places the cylinder at the rear of the piston in communication with 5 said chamber.

5. In a rock drill, in combination, a cylinder, a reciprocating part in said cylinder, a drill steel connected to said part, a passage through said part and steel for 10 leading water to the bore hole, a tube connected to the cylinder and over which the piston works, a chamber in said reciprocated part around the tube, a bush fitted in the reciprocated part, which bush works loosely 15 over the tube thereby placing the interior of the cylinder at the back of the piston in

communication with said chamber to admit and maintain a supply of air under pressure to said chamber during the forward stroke of the piston, as and for the purpose set 20 forth.

In testimony whereof we have signed our names to this specification in the presence of two subscribing witnesses.
